GUN

Clair W. Wadsworth, Fulton, N. Y., assignor to
Hunter Arms Co., Inc., Fulton, N. Y., a corpora-
tion of New York

Application April 12, 1934, Serial No. 720,252

5 Claims.

(Cl. 42—2)

This invention relates to guns, and has for its object a gun lock action which is particularly simple and economical in construction and which contains no delicate parts to get out of order.

5 It further has for its object a gun lock mechanism in which the motion of the trigger is transferred to the hammer to retract and release it through a thrust member or sear acting through a lever or other movable member coacting with 10 the hammer and on which lever the spring, which urges the hammer, acts.

It further has for its object the assembly of the parts of the gun lock mechanism including a hammer actuated by a spring-pressed lever, in 15 the frame with particular reference to the location of a long or large hammer actuating lever in the hand or pistol grip of the gun.

It further has for its object a hammer construction in which the firing pin is an integral 20 part of or fixed to the hammer to move therewith together with means for retracting the hammer far enough to withdraw the end of the firing pin out of the firing chamber when the gun is idle or the gun lock mechanism in normal 25 or starting position.

It further has for its object an assembly of the barrel of the gun in a block which coacts with the breech block of the frame, the barrel telescoping into and snugly fitting the bore of the 30 first block.

The invention consists in the novel features and in the combinations and constructions herein-after set forth and claimed.

In describing this invention, reference is had 35 to the accompanying drawing in which like characters designate corresponding parts in all the views.

Figure 1 is a fragmentary side elevation, partly 40 in section and parts being removed, of a gun embodying my invention.

Figures 2 and 3 are respectively sectional views on lines 2—2, 3—3, Figure 1.

The gun here illustrated is for firing cartridges containing gas, as tear gas. The gun lock mechanism comprises generally a hammer movable 45 forwardly and rearwardly in the frame and preferably being slidably mounted in the frame, a hammer actuating lever arranged in the frame at an angle to the direction of movement of the 50 hammer and being here illustrated as pivoted at a point remote from the hammer, that is, at its lower end in the frame and being articulated at its upper end into the handle, the lever extending into the pistol grip of the gun, a trigger mechanism including a trigger pivoted in the

frame and a thrust member, sear or latch preferably pivoted thereto at one end and thrusting at its other end against the lever and being guided in the frame, the sear and lever having coacting shoulders which ratchet out of engagement with each other when the trigger has been pulled far enough to cock or retract the hammer and thus release the lever, and hence the hammer, so that the hammer can be impelled forwardly by a spring which acts on the lever.

The lock mechanism further comprises a hammer having the firing pin fixed thereto so as to move as a unit therewith and a lost motion connection between the lever and the hammer, and a spring for taking up the lost motion to retract 15 the hammer sufficiently to withdraw the firing pin out of the firing chamber when the firing mechanism is in starting or normal position.

1 designates generally the frame of the gun which is formed with a breech block 2 and with 20 a pistol grip portion 3. 4 is the stock secured to the frame in any well known manner. The frame encloses an internal cavity including an upper horizontal portion 5 and upright portion 6 extending into the pistol grip 3. The sides of the 25 frame are covered with the usual plates and grip panels, not shown.

7 designates a block hinged at 8 to the forwardly extending portion 9 of the frame, this block being formed with a bore 10 for receiving 30 a tubular barrel 11. The bore of the block tapers as shown from the rear or breech end toward the front end; and the barrel or tube 11 is also tapered the full length thereof from its rear end forwardly and the tube pressed into the bore of 35 the breech block from the breech block end thereof, the rear portion of the barrel located in the block forming the greater part of the chamber for the cartridge 13.

14 designates a portion of the extractor mechanism which pushes out the cartridge when the barrel mechanism is moved about the pivot 8 to open the breech of the gun. The extractor mechanism may be of any suitable construction and forms no part of this invention.

15 designates a latch for holding the breech closed and operable to permit the breech to open, this latch mechanism forming no part of the invention and may be of any suitable form, size and construction.

16 designates the hammer, this being slidably mounted to move forwardly and rearwardly rectilinearly in suitable guide passages formed in spaced apart lugs 17, 18 in the frame, and 19 is a firing pin which is fixed to the hammer and 55

usually is an integral part thereof, this moving through a suitable passage in the breech block and operable to project the nose thereof into the firing chamber to fire the cartridge when the hammer is operated.

20 designates the hammer operating member or lever extending at an angle to the direction of movement of the hammer, this extending downwardly into the chamber 6 of the pistol grip 10 and being pivoted at 21 at its lower end, the upper end being pivotally connected, or articulated, to the hammer and by a lost motion connection for a purpose to be presently described. The lever 20 is urged forward to actuate the hammer 16 by a spring 22 in the chamber 6 and interposed between the rear wall of the chamber and the rear side of the lever 20. The forward motion of the lever under the action of the spring is limited by a stop shoulder or shoulders 23.

20 The trigger mechanism includes a trigger 24 and a thrust member or sear 25 coacting therewith and with the lever, it coacting with a ratcheting action with one of the parts with which it coacts, preferably the lever 20, in such a manner that the trigger mechanism is single acting, that is, it cocks and releases the hammer upon a single pull of the trigger. The trigger 24 is here shown as pivoted at 26 within the frame above the hammer and extends downwardly 30 crosswise of the front portion of the hammer into the trigger guard opening 27. 28 is a trigger spring serving to press it forwardly into its normal or starting position against the stop 29. The upper portion of the trigger is bifurcated providing a passage between the bifurcations through which the hammer 16 moves.

The sear or thrust member 25 is preferably pivoted at 30 to the trigger below the hammer and extends in a general horizontal direction 40 rearwardly through a guide passage 31 in the lug 18 and normally thrusts at its rear end against the lever 20. The sear is thrust upwardly about its pivot 30 against the upper wall of the guide passage by a spring 32 interposed between 45 the sear and the trigger, the sear extending between the bifurcations of the trigger.

The sear and the lever 20 coact with a ratcheting action which permits the sear to ratchet out of engagement with the lever when the trigger 50 has been actuated far enough to pull back the hammer and, as here illustrated, the lever 20 is formed with a passage 33 therethrough and with a shoulder 34 at the front end of the passage against which a nose or corner 35 at the rear 55 end of the sear thrusts. The passage is so relatively arranged that when the trigger is pulled, the sear thrusts against the shoulder 34 and hence swings the lever 20 backwardly against the action of the spring 22 retracting the hammer therewith. When the hammer has been retracted, owing to the pivotal position of the trigger, the pivotal position of the lever 20 and the coaction of the pivoted sear 25 with the upper wall 31^a of the guide passage 31, the sear 25 will 60 ratchet out of engagement with the shoulder 34 or rather the passage 33 will be brought into alignment with the sear 25, and the shoulder 34 will ratchet out of engagement with the nose 35 of the sear, so that the spring 22 is free to react 65 and press the lever 20 forwardly, the sear then passing into the passage 33. The forward motion of the lever under the influence of the spring 22 actuates the hammer to fire the cartridge.

The lost motion connection between the lever 75 20 and the hammer, as here illustrated, com-

prises a fork 36 at the upper end of the lever extending astride the hammer, and the hammer being formed with grooves, as 37, on opposite sides for receiving the bifurcations of the fork. The width of the grooves 37 is slightly greater than the width of the bifurcations to provide a lost motion between the lever 20 and the hammer 16, and the hammer is provided with a compression spring 39 located internally thereof and thrusting at one end against the rear sides of the bifurcations of the fork and at its rear end against a suitable spring abutment 38 at the rear of the hammer. When the parts of the gun mechanism are in their starting or normal position, as shown in Figure 1, the lever 20 is against the stop 23, and the spring 39 is free to react to pull the hammer slightly rearwardly far enough to pull the nose of the firing pin 19 out of the firing chamber. When the trigger 24 is pulled, the sear 25 thrusts against the lever 22 and moves the lever rearwardly on its pivot against the action of the spring 22. It also compresses the spring 39 until the yoke 36 engages the rear walls of the grooves 37 so that further movement retracts the hammer. As the trigger approaches the end of its rearward pull, the sear ratchets out of engagement with the lever, permitting the spring 22 to react and the hammer 16 to be urged forward, projecting the nose of the firing pin into the cap of the cartridge, firing the cartridge. When the lever comes up against the stop 23, the spring 39 is free to react slightly withdrawing the hammer 16 and the firing pin 19 so that its nose is out of the firing chamber, and does not interfere with the extracting of the cartridge and the insertion of a new one.

What I claim is:

1. In a gun, a frame, and gun lock mechanism comprising a hammer movably mounted in the frame, a lever element extending at an angle to the direction of movement of the hammer, and pivoted to the frame at a point remote from the hammer and being pivotally connected directly to the hammer, a spring acting on the lever to press it in a direction to actuate the hammer, a trigger element mounted in the frame and a sear coacting with the trigger element and with the lever element, the sear coacting with a ratcheting action with one of the elements with which it coacts to shift out of engagement therewith when the trigger is pulled far enough to actuate the lever to retract the hammer.

2. In a gun, a frame formed with a horizontally extending chamber and a downwardly extending chamber in the portion of the frame which constitutes the frame of a pistol, a hammer slidably mounted in the horizontally extending chamber and movable lengthwise thereof, a lever arranged at an angle to the hammer and extending into the downwardly extending chamber and being pivoted therein, said lever being articulated at its upper end to the hammer, a spring acting on the lever to force it in a forward direction to actuate the hammer, a trigger pivoted in the frame above the front end of the hammer and extending downwardly crosswise of the hammer, a sear located within the frame and coacting at its front end with the trigger and at its rear end with the lever, the frame being formed with a guide for the sear, the sear and one of the parts with which it coacts having ratcheting means for releasing the lever when the trigger has been pulled far enough to retract the hammer.

3. In a gun, a frame, and a gun lock mechanism in the frame comprising a firing pin, a

slidable hammer fixed to the firing pin so that the firing pin and hammer move as a unit, a single acting trigger mechanism for cocking and releasing the hammer, a member actuated by the trigger for retracting the hammer, said member being connected to the hammer by a lost motion connection, a spring acting on said member for pressing the same forwardly to actuate the hammer, a stop limiting the forward movement 5 of the lever, and a second spring interposed between said member and the hammer for taking up the lost motion in a retrograde direction to withdraw the hammer far enough to withdraw the firing pin out of the firing chamber, when 10 said member is against the stop.

4. In a gun, a frame formed with a firing chamber and a gun lock mechanism comprising a hammer movable in a horizontal direction in the frame, a firing pin secured to the hammer 20 and movable therewith, a single action trigger actuated mechanism operable to cock and release the hammer on a single pull thereof including a member coacting with the hammer, a spring acting on said member to urge the hammer forwardly, a stop for limiting the forward move- 25

ment of said member, the hammer being formed with a chamber at the rear of said member, a spring in said chamber and acting upon said member whereby when said member is against the stop the last named spring acts to retract 5 the hammer relatively to said member far enough to withdraw the firing pin clear of the firing chamber.

5. In a gun, a frame formed with a firing pin chamber, and a gun lock mechanism comprising 10 a hammer, a firing pin secured to the hammer and movable in the frame to project into the firing chamber, a single acting trigger mechanism operating to retract and release the hammer and firing pin upon a single pull of the trigger, the 15 trigger actuated mechanism including a member connected to the hammer by a lost motion connection, a spring acting on said member to actuate the hammer forwardly, a stop limiting the forward movement of said member and means 20 for taking up the lost motion of said connection and retracting the hammer relatively to said member when said member is against the stop.
